UNITED STATES PATENT OFFICE.

EDWARD P. CALDWELL, OF CHICAGO, ILLINOIS, ASSIGNOR, BY MESNE ASSIGNMENTS, TO THE GRAHAM ELECTRIC COMPANY, OF SAME PLACE.

ACETYLENE-GAS GENERATOR.

SPECIFICATION forming part of Letters Patent No. 651,840, dated June 12, 1900.

Application filed August 19, 1899. Serial No. 727,751. (No model.)

To all whom it may concern:

Be it known that I, EDWARD P. CALDWELL, a citizen of the United States, residing at Chicago, in the county of Cook and State of Illinois, have invented certain new and useful Improvements in Gas-Generators, of which the following is a specification, reference being had to the accompanying drawings.

My invention relates to machines for generating gas by the union of a liquid and a solid, and is primarily designed for the production of acetylene gas.

It has for its object the construction of a machine for such purpose that will be cheap, simple, and effective and in which the supply of solid material to the liquid will be automatically effected by the action of the bell or movable portion of the gas-holder upon means through which valves in the carbid-receptacle are operated. This object I accomplish as illustrated in the drawings and hereinafter described.

That which I believe to be new will be pointed out in the claims.

In the accompanying drawings, Figure 1 is a vertical longitudinal section of the gas-generating apparatus. Fig. 2 is a sectional detail view of the carbid receptacle or holder for solid material.

Referring to such drawings, A represents the fixed portion of a gas-holder adapted to contain water, as usual, and B represents the ordinary bell or movable portion of such holder within the fixed portion.

C represents the gas-generating chamber, located below the gas-holder, and which in the construction shown is formed integral with the fixed portion A of such holder, the two being separated by a horizontal partition a.

The bottom b of the generating-chamber C is formed on an incline, as shown, in order that the refuse from the used carbid may be directed thereby to one side of the chamber and be the more readily drawn off or taken out through a suitable opening in the side of chamber. As shown, an ordinary cock c is inserted through the wall of such chamber at a point opposite the lower end of such inclined bottom, through which cock the refuse matter may be drawn off.

D represents a carbid-receptacle in the form

of a tube, the lower end of which is open and communicates with the chamber C through an opening in a lateral extension of the horizontal partition a, upon which partition said carbid-receptacle is located. The upper end of this receptacle is to be closed by a cap d or other suitable device. Within the carbid-receptacle and pivoted on opposite sides thereof are two valves E E', held normally in a closed position by suitable springs to prevent the downward passage of carbid, the springs shown being ordinary coiled springs attached at one end to the valves and at the other end to the wall of the tube D at points above the valves, such springs being indicated, respectively, by e e'. These springs being located within the carbid-chamber are necessarily surrounded with the carbid that is held in said chamber by the valves E E', and as the valves are opened and closed from time to time the springs of course are extended and retracted, and such action of the springs produces an agitation of the carbid that tends to loosen the mass, and thus overcomes any tendency of the carbid to clog in the receptacle D and be thereby prevented from freely and quickly falling when the valves are opened. To the said valves are attached, respectively, rods F F', which pass down into the generating-chamber C, their lower ends being secured, respectively, to levers G G', hinged to the casing of the chamber C, as indicated at f f'. To the outer end of each lever G G' is pivoted, as shown at g g', a vertical rod H H', respectively, which rods pass up through an opening in the horizontal partition a and through pipes h h', respectively, such pipes projecting beyond the water in the gas-holder and serving as guides for the rods. As shown, each of the rods is long enough to be acted upon by the top of the bell or movable portion B of the gas-holder before such bell or movable portion reaches the limit of its descent. It will also be seen that one of the rods—to wit, rod H—is extended upward farther than the other and will of course be acted upon by the bell or movable portion B in its descent before the other rod is so acted upon.

I is a pipe open at its lower end only and communicating through an opening in the

horizontal partition *a* with the chamber *C*. Near the top of said pipe is suitably secured a short section of pipe *i*, communicating at one end with the interior of the pipe *I* and 5 depending so that its other end is below the surface of the water in the gas-holder.

J is a passage for gas from the gas-holder, and, as shown, is formed of a piece of pipe of 10 large diameter open at both ends and passing through suitable openings in the horizontal partition *a* and the inclined bottom *b* of the gas-generating chamber *C*. Its upper end opens into the gas-holder above the water 15 therein, and its lower end opens into a receptacle *K* beneath the inclined bottom *b*, such receptacle and the passage *J* both being adapted to contain a supply of charcoal or other suitable matter adapted to purify the gas.

L indicates a pipe leading from the receptacle *K* and intended to convey the gas generated in the chamber *C* to the place of consumption.

With the device in use and a supply of carbide in the receptacle *D*, as represented, when 25 the quantity of gas in the holder is reduced through being drawn off for use the bell or movable part *B* of said holder of course gradually descends, and when sufficient gas has been drawn off the said bell or movable part 30 will come in contact with the uppermost one of the projecting rods *H* and force it down, the effect being, through the lever *G* and rod *F*, connected therewith, to cause the valve *E* to be pulled down and allow a small quantity of carbide to fall into the chamber *C*, and as it comes 35 into contact with the water in such chamber gas will of course be immediately evolved and will rise and pass through the pipes *I* and *i*, and from the water, into which it passes as 40 it leaves the pipe *i*, will pass into the gas-holder. Now if gas in sufficient quantity has been evolved the pressure will of course raise the bell or movable part *B*, releasing the pressure on the rod *H*, allowing the spring *e* to 45 close the valve *E*, and shutting off the supply of carbide. If, however, not enough carbide is delivered by the opening of the valve *E*, as described, to generate a sufficient quantity of gas, the farther sinking of the bell or movable 50 portion *B* will bring its top also in contact with the upper end of the lowermost rod *H'*, and through it lever *G'* and rod *F'* will open the valve *E'*, and both valves being thus 55 opened will allow carbide to descend in quantity sufficient to immediately generate a supply of gas the pressure of which will raise the bell or movable portion *B*, both valves being closed, of course, by the action of their respective springs *e* *e'* immediately upon the 60 pressure on the bell being removed from the upper ends of the rods *H* *H'*.

By the means shown and described gas can be quickly and economically generated and with but little attention on the part of the 65 user beyond filling the receptacle *D* from time to time as needed with fresh carbide and removing the refuse from the chamber *C*, which

latter operation is greatly facilitated by providing the inclined bottom *b*, which of course directs all refuse solid matter to one side of the chamber, at which side is located the opening through which the refuse is removed or drawn off. Constructing the generating chamber with such an inclined bottom also furnishes a large and conveniently-located receptacle in which a sufficient quantity of charcoal or other purifying agent may be stored, through which the gas may pass before it is taken out through the supply-pipe *L* for consumption.

That which I claim as my invention, and desire to secure by Letters Patent, is—

1. In a machine for generating gas by the union of a solid and a liquid, the combination of a gas-holder comprising a fixed portion 85 and a movable portion, a gas-generating chamber below and in communication with said gas-holder and adapted to contain liquid, a receptacle for containing solid material to be discharged into the gas-generating chamber, 90 a plurality of valves located in said receptacle to control the discharge of the solid material to the gas-generating chamber, lever mechanism and connected rods for successively opening said valves by the continued 95 downward movement of the movable portion of said gas-holder, whereby each of said valves may be open at the same time to allow an increased quantity of the solid material to pass to the generating-chamber, and means for automatically and successively closing said valves as said movable portion of the gas-holder rises, substantially as and for the purposes described.

2. In a machine for generating gas by the 105 union of a solid and a liquid, the combination of a gas-holder comprising a fixed and a movable portion, a gas-generating chamber communicating with said gas-holder and adapted to contain liquid, a receptacle for 110 containing solid material communicating with the gas-generating chamber, a plurality of valves controlling admission of the solid material to the generating-chamber, rods attached at one end to said valves, pivoted levers to which the other ends of said rods are 115 attached, and other rods attached to and projecting upward from said levers to different heights and thereby adapted to be successively operated upon by the movable portion 120 of the gas-holder, substantially as and for the purpose specified.

3. In a machine for generating gas by the union of a solid and a liquid, the combination of a gas-holder comprising a fixed and a 125 movable portion, a gas-generating chamber communicating with said gas-holder and adapted to contain water, a receptacle for containing solid material communicating with the gas-generating chamber, a plurality of 130 valves controlling the admission of the solid matter to the generating-chamber, and a plurality of rods connected with said valves and extended upward to different heights where-

by they are adapted to be successively acted upon by the descent of the movable portion of the gas-holder, substantially as and for the purpose specified.

- 5 4. In a machine for generating gas by the union of a solid and a liquid, the combination of a gas-holder comprising a fixed and a movable portion, a gas-generating chamber communicating with said gas-holder and adapted to contain water, a receptacle for containing solid material communicating with the gas-generating chamber, a plurality of valves controlling the admission of the solid matter to the generating-chamber, a plurality of rods located within the generating-chamber and the gas-holder and extended upward to different heights whereby they are adapted to be successively moved by the contact therewith of the movable portion of the gas-holder 15 in its downward movement, and means for connecting said rods and valves so that they

will move together, substantially as and for the purpose specified.

5. In a machine for generating gas by the union of a solid and a liquid, the combination with a gas-generating chamber adapted to contain a liquid, of a solid-containing receptacle communicating with said generating-chamber, a valve in said receptacle for controlling the flow of solid material to the 25 gas-generating chamber, means for opening said valve, and a spring for closing said valve, said spring being located in the solid-containing receptacle above the valve and being adapted to agitate said solid material during 30 the act of operating the valve, substantially as and for the purpose specified.

EDWARD P. CALDWELL.
